SEWING MACHINE ATTACHMENT

Sam F. Iogha, Hornell, N. Y.

Application March 10, 1936, Serial No. 68,131

5 Claims. (Cl. 112—239)

This invention is an attachment adapted to be readily applied to sewing machines, particularly sewing machines of the type used in repairing and in the making of shoes, and where by the 5 use of said attachment the sewing machine may be used for darning purposes.

Among the objects of the invention is to provide an attachment of this character which may be readily and easily applied to the machine, and 10 which attachment itself can be cheaply and economically constructed and will serve admirably the purposes for which it is designed.

The invention together with its objects and 15 advantages will be best understood from a study of the following description taken in connection with the accompanying drawings wherein:

Figure 1 is an elevational view illustrating the application of the attachment to the sewing machine.

Figure 2 is a longitudinal sectional view through 20 the attachment.

Figure 3 is a plan view of the attachment.

Figure 4 is a fragmentary elevational view of 25 the end portion of the body member of the attachment adapted to be connected with the presser foot rod.

Figure 5 is an elevational view of a slightly modified form of the invention.

Figure 6 is a longitudinal sectional view through 30 the second form of the invention.

Figure 7 is a top plan view of the second form of the invention.

Figure 8 is an elevational view of still another 35 form of the invention.

Figure 9 is a longitudinal sectional view through the third form of the invention.

Figure 10 is a top plan view of the third form of the invention.

In accordance with the present invention the 40 attachment is for the purpose of simplifying the operation of darning on a patching machine; the invention comprehending the provision of means whereby a quick change over from stitching to darning or vice versa on sewing machines 45 may be accomplished.

In accordance with the present invention it will be noted, that in each form thereof the attachment comprises a substantially cylindrical solid body member 5 provided at its respective upper 50 and lower ends with non-circular portions 6 and 7 respectively for the application thereto of a tool or the like for applying or removing the body member from the rod 8 of a conventional sewing machine, and which rod carries the usual 55 presser foot 9.

In Figure 1 there is shown fragmentarily the head portion of a sewing machine and in this figure in addition to the rod 8 and presser foot 9 there is also clearly shown the vertically movable needle bar 10 to which is detachably secured 5 in the usual manner and as indicated at 11 the needle 12.

In the form of the invention shown in Figures 1 to 4 inclusive the member 5 in the lower end thereof is provided with a threaded socket 13 into which is threaded one end of a coupling pin 14.

Also in this form of the invention the presser foot rod 8 is provided with a threaded socket 15 in the upper end thereof into which is threaded a second end of the pin 14 as indicated generally at 16 in Figure 1.

Also the member 5 in the upper end thereof is provided with a threaded socket 16 into which is screwed an end of the threaded shank of a head 20 equipped screw 17.

Also in this form of the invention the shank of the screw 17 is threaded through a suitable opening provided in a tapered arm 18 that extends laterally from the screw in the path of the needle 25 bar 10.

In actual practice it will be apparent that during the operation of the machine for sewing in the usual manner the arm or plate 18 is swung to a position at an angle to that shown in the 30 drawings so as to be out of the path of the needle bar 10. Thus the machine will work in the usual manner.

As is well known, when darning, it is essential that both the needle and the presser foot be in 35 a clear position so that the operator can move the material in any direction. Therefore, and as will be manifest, in accordance with the present invention the presser foot will move along with the needle bar on the upward motion of the 40 latter as the latter comes out of the work. Thus when the darning arm of plate 18 is threaded downwardly on the shank of the screw 17, and when said arm is in its lowermost position, which is the position shown in Figure 1, the arm or 45 plate 18 will have the free end thereof disposed in the path of the needle bar 10. Thus it will be seen that when using the machine for darning, the needle bar 10 on each upward movement thereof will come into contact with the plate 50 or arm 18 with the result that the presser foot bar 8 will be caused to move upwardly with the needle bar 10. Thus both the needle 12 and the presser foot 9 will be in a clear position permitting the operator to move the material in any 55

direction necessary to accomplish the darning of the object being worked upon.

In the form of the invention shown in Figures 5 to 7 inclusive screw 17 and plate 18 may be dispensed with, and in this second form of invention the body member indicated by the reference numeral 5a has in the upper end thereof a vertical socket 19, and at opposite sides of the socket 19 the upper end of the body member 10 5a is provided with alined openings 20. A headed pin or arm 21 has a sliding fit in the alined openings 20 and the pin 21 is retained in either of the two positions suggested in Figure 5, frictionally, through the medium of a spring 22 arranged 15 within the inner end of the socket 19 and having an end bearing against the pin or arm 21.

In this form of the invention the arm 21 is the equivalent of the plate or arm 18 described in the first form of the invention and when in 20 the full line position shown in the drawings the free end of the pin 21 will be in a position to be engaged by the needle bar 10 each time that bar is raised during the darning operation. When in the broken line position suggested in 25 Figure 5 the free end of pin 21 will be out of the path of the needle bar 10 so that the sewing machine may be used for sewing in the usual manner.

Also in this second form of the invention the 30 body 5a is attached to the presser foot bar through the medium of a threaded pin 23 one end of which is screwed into the lower end of the body member 5a and the other end of which is adapted to be threaded into the upper end of 35 the presser foot bar 8 as is thought to be apparent.

In the form of the invention shown in Figures 8 to 10 the body member, indicated by the reference numeral 5b is provided in the lower end 40 thereof with a socket 24 the walls of which are smooth and this socket is adapted to receive the upper end of the presser foot bar 8a in a manner clearly shown.

Threadedly engaged with opposite sides of the 45 lower end of the body member 5b are securing screws 25 which are adapted to be screwed inwardly to binding engagement with the end of the presser foot bar 8a received within the socket 24 as shown in Figure 9 for positively securing 50 the member 5b to the presser foot bar.

From the foregoing, it will be seen that I have provided an attachment for a patching machine whereby such a machine may be readily changed over from a patching or darning machine to a 55 stitching machine or vice versa.

It will also be further appreciated that the device forming the subject matter of this invention when in actual use on the machine will not only cause the presser foot to move with the 60 needle bar but will also prevent the presser foot from dropping when the tension thereon is removed. Also the attachment, or the use thereof,

will eliminate the necessity for threading the needle for darning as well as for adjusting the tension on the presser foot to allow sufficient clearance for darning.

Having thus described the invention, what is 5 claimed as new is:

1. The combination with the needle and presser bars of a sewing machine, of a member mounted on the upper end of the presser bar, an arm mounted on said member for sliding movement 10 transversely thereof into and out of position within the path of the needle bar, and yielding means engaged with said arm for frictionally retaining the same in either of two positions.

2. The combination with the needle and presser bars of a sewing machine, of a member arranged on the upper end of the presser bar, means detachably connecting one end of said member with the upper end of the presser bar, an arm extending laterally from said member 20 and a screw threadedly engaged with said arm and the upper end of said member attaching the arm to said member, said arm being rotatable about the screw as an axis and axially movable relative to said screw into and out of the path 25 of the needle bar.

3. The combination with the needle and presser bars of a sewing machine, of a member adapted to be mounted on the upper end of the presser bar, means detachably connecting said member 30 with the upper end of said presser bar, said member at the upper end thereof being transversely bored, a rod having a sliding fit within said bore and adapted to be projected laterally from said member for disposition within the 35 path of the needle bar, said member at the upper end thereof being also provided with a socket bisecting said bore, and a spring arranged in said socket and having an end bearing against said rod for holding the latter in either of two positions.

4. A sewing machine attachment comprising a body provided at one end for attachment to the upper end of the presser bar of a sewing machine and for attachment to and removal from said end of the presser bar in a direction axial to the presser bar, and means detachably connected with the free end of said body and shiftable relative thereto for movement into and out of the path of the usual needle bar of a sewing machine 45 as and for the purpose specified.

5. A sewing machine attachment comprising a member provided at one end for axial and detachable association with the upper end of the presser bar of a sewing machine and means 55 associated with the free end of the member and movable relative thereto and in a plane at right angles to the plane of said member for position into and out of the path of the needle bar of the sewing machine, as and for the purpose 60 specified.

SAM F. IOGHA.
